PROCESS AND APPARATUS FOR WINDING
FILAMENTS

John William Allquist, Rome, Ga., assignor to
Tubize Chatillon Corporation, New York, N. Y.,
a corporation of Delaware

Application October 5, 1938, Serial No. 233,403

9 Claims. (Cl. 18—8)

This invention relates to winding plastic filaments, particularly freshly formed rayon filaments, and aims to inhibit the development of non-uniform denier or cross-section during the winding of such filaments as a series of overlapping spirals on a bobbin or other retaining means.

It is customary to wind freshly spun rayon filament bundles or yarns upon a bobbin or the like while the rayon is still in a plastic condition. Thus, rayon yarn frequently is wound on bobbins almost immediately after withdrawal from a setting bath or solvent evaporating chamber. In such procedure, the fresh yarn passes through a reciprocating guide and then is wound as a cake on a rapidly rotating bobbin. The guide reciprocates or oscillates back and forth along the length of the bobbin transversely to the direction of passage of the yarn so as to distribute the yarn on the bobbin as a series of overlapping spirals. As the guide changes direction at the end of a stroke, it exerts an uneven strain on the plastic yarn and causes it to become stretched and distorted, this distortion being manifested by a lack of uniformity in the cross-section or denier of the yarn. Various means have been proposed heretofore with a view toward minimizing the distortion thus caused, and have taken the form of complex mechanisms for reducing the speed of the guide toward the end of the stroke so as to reduce the strain upon the yarn at the moment that the guide changes direction. Such proposals, however, have not been entirely satisfactory. At the present time, commercially produced yarns averaging, say 150 denier, have variations of from 140 to 160 denier, or even more over a length of about 1 meter, as a result of the action of the traverse mechanism.

As a result of my investigations, I have discovered that the aforementioned distortion during the winding of fresh rayon and similar plastic filaments may be inhibited if tension in the filaments is reduced and substantially equalized at the point where they are wound onto and become part of a cake on the bobbin. It is probable that the filaments have sufficient inherent resiliency to restore them to the form they had prior to distortion by the alternate pull and release of the guide. Whatever the explanation, the fact remains that the cross-section of fresh-wound rayon yarn is more uniform if it is slackened or substantially untensed after passing through a traverse and before it is wound. In accordance with my invention, the requisite

reduction and equalization in tension at the point of winding is obtained by passing the filaments moving from the guide to the bobbin against a surface moving in the direction of passage of the filaments at a speed that is substantially higher than the peripheral speed of the cake being formed on the bobbin, while moving the filaments back and forth across the surface transverse to the direction of passage and, in effect, in the direction of the stroke of the guide. In this way, the traverse motion imparted to the filaments by the guide is not interfered with substantially, and the yarn may be wound in the desired series of overlapping spirals while in a slack or relatively untensed condition. The filaments should be pressed against the moving surface with a force sufficient to permit the transmission of power from the surface to the filaments, so that the latter are accelerated. In other words, there should be sufficient friction between filaments and moving surface to permit acceleration of the filaments but not so much that the transverse motion of the filaments across the surface is prevented. The surface is preferably a rotating annular one, for example, that of a relatively long cylinder mounted with its axis of rotation substantially parallel to that of the bobbin or other rotating collector. The surface, for example, that of a positively driven cylindrical godet, should be at least as long as the cake or yarn package to be formed. Otherwise, the filaments tend to run off the ends of the surface. No further guides or traverses should be interposed between the driven godet or like member and the bobbin or other yarn winding means, because these would tend to make yarn tension unequal again and undo the good done by the driven godet. In other words, the yarn should not bear against any member which might re-introduce inequality of tension as it passes from the driven godet to the bobbin.

In summary, my invention contemplates the improvement in a process in which plastic filaments are passed through a reciprocating guide and wound as a cake on a rotating bobbin which comprises passing the filaments moving from the guide to the bobbin against a surface moving in the direction of passage of the filaments at a speed that is substantially higher than the peripheral speed of the cake, transmitting power from the moving surface to the filaments and thereby accelerating the filaments while moving the filaments back and forth across the surface transverse to their direction of passage, whereby

tension in the filaments at the point of winding on the bobbin is reduced. My invention further contemplates the combination in apparatus for winding plastic filaments which comprises a rotatable bobbin upon which the filaments are wound, means for rotating the bobbin, a guide through which the filaments pass on their way to the bobbin, said guide being reciprocable through a stroke transverse to the direction of passage of the filaments, a godet so disposed in the path of the filaments from the guide to the bobbin that the filaments bear against the godet, and the means for rotating the godet in the direction of filament passage at a peripheral speed substantially in excess of that of the bobbin, the coefficient of friction of the godet being such that the higher peripheral speed thereof is transmitted at least in part of the filaments. By "peripheral speed of the bobbin" I mean linear speed of the yarn at the point where it is wound onto the cake being built up on the bobbin. These and other features of my invention will be understood more thoroughly in the light of the following detailed description taken in conjunction with the accompanying drawing, in which

Fig. 1 is a schematic transverse elevation of one form of the apparatus of my invention;

Fig. 2 is a schematic longitudinal elevation of the apparatus of Fig. 1;

Fig. 3 is a schematic transverse elevation of another form of the apparatus of my invention; and

Fig. 4 is a schematic longitudinal elevation of the apparatus of Fig. 3.

Referring now to the drawing, the apparatus of Figs. 1 and 2 comprises a bobbin 10 of conventional type rigidly mounted in a horizontal position on a concentric shaft 11. Conventional means, such as a belt-driven pulley 11a, are provided for rotating the shaft. Disposed directly above the bobbin and parallel to it is a godet 12 rigidly mounted on a shaft 13, which is adapted to be positively driven by a means, such as a belt-driven pulley 13a, at a rate such that the peripheral speed of the godet is substantially higher than that of the bobbin. The godet is in the form of a smooth surfaced cylinder, the length of which is substantially the same as the length of the bobbin, both godet and bobbin being longer than the traverse stroke, as hereinafter described.

Freshly formed and, therefore, plastic rayon filaments are produced in the form of yarn 14 comprising a plurality of filaments. The yarn is passed through a traverse 15 of conventional form having a guide 16 mounted at the extremity of an arm or pendulum 17. Means (not shown) are provided for swinging the traverse arm back and forth so that the guide reciprocates in a direction transverse to that of yarn passage (as indicated by the arrows on Fig. 2), and substantially parallel to the axes of rotation of the godet and of the bobbin. The yarn passes through the reciprocating guide and is wound as a cake 18 on the bobbin. The cake comprises a series of overlapping spirals and if the traverse stroke is gradually shortened during the winding operation, it will have tapered ends as shown in Fig. 2.

Ordinarily, yarn need not pass completely around the godet. Generally, contact of the yarn with only a relatively small portion of the periphery of the godet will be sufficient to impart to the yarn the requisite acceleration. In some instances, however, as when the godet surface has

a very low coefficient of friction, it may be desirable to pass one or more turns of the yarn around the godet so that there will not be excessive slippage of the yarn with respect to the godet surface. With ordinary machined metal surfaces, the yarn need take only about half a turn around the godet which, being driven at a substantially higher speed than the bobbin, will cause a portion 19 of the yarn between the godet and bobbin to be in a slack or relatively untensed condition. In such condition, the natural resiliency of the rayon yarn will result in at least a partial removal of the distortion in cross-section brought about by the uneven strain imposed by the reciprocating traverse guide. Consequently, the character of the yarn will be improved. Thus, in accordance with my invention, variations in denier may be reduced to 2 or 3% or less.

The apparatus of Figs. 3 and 4 is the same in principle as that of Fig. 1, but in it the freshly spun rayon yarn 29 first is passed over a first godet 30 which may be part of the stretching arrangement customarily employed for reducing the denier of freshly spun yarn. As shown in Fig. 4, the godet 30 need not be very long because the yarn follows a substantially constant path around its surface. After the yarn passes over the first godet, it passes through a guide 31 mounted on the end of a traverse arm 32 which in this instance is reciprocated lengthwise in a direction transverse to the direction of yarn passage and substantially parallel to the axis of the godet. Below the guide, the yarn passes against a second godet 33, changes direction, and is wound as a series of overlapping spirals in a cake 34, on a bobbin 35. The bobbin is rigidly mounted on a horizontally disposed shaft 36 and conventional means (not shown) are provided for driving the shaft. The axes of both godets and the bobbin are substantially parallel.

The second godet 33 is cylindrical in form, of relatively small diameter, and at least as long as the traverse stroke, so that the yarn will not be thrown off its ends. It is mounted out of line with the common tangent of the first or upper godet and the bobbin, so that the yarn in passing over it changes direction and bears against a portion of the second godet's periphery. Conveniently, the second godet is rigidly mounted on a shaft 37, which is positively driven, by a means such as gearing 38, at a rate such that the peripheral speed of the second godet is in excess of that of the bobbin.

As in the case of the apparatus of Figs. 1 and 2, the second godet 33 of the apparatus of Figs. 3 and 4 is rotated in the direction of yarn passage, accelerates the yarn passing over it so that a section 39 of the yarn between the second godet and the bobbin is in a relatively untensed or slack condition. In this condition the yarn has an opportunity to resume its original shape and its resiliency acts to overcome the distortion in denier brought about by the alternate drag and release of the traverse mechanism. Hence, by relatively simple means, I am able to improve the uniformity of rayon yarn and the like.

In the practice of my invention the peripheral speed of the driven godet interposed between the traverse and the bobbin will depend upon the amount of slippage which occurs between this godet and the yarn. This in turn depends upon the length of yarn in contact with the godet and upon the degree of friction between godet and yarn. Generally speaking, however, there

will be no appreciable slippage if 90 degrees of the periphery of a godet of normal size is in contact with the yarn at a given instant, in which case the peripheral speed of the godet should be about 3% more than the peripheral speed of the bobbin.

Any suitable form of driving mechanism such as a motor geared to the traverse, the bobbin and the driven godet may be employed. If desired, the gears may be so arranged as to maintain a fixed ratio between the speeds of the driven godet and the bobbin.

I claim:

1. In a process in which plastic filaments are passed through a reciprocating guide and wound as a cake on a rotating bobbin, the improvement which comprises passing the filaments moving from the guide to the bobbin against a surface moving in the direction of passage of the filaments at a speed that is substantially higher than the peripheral speed of the cake, transmitting power from the moving surface to the filaments and thereby accelerating the filaments, while moving the filaments back and forth across the surface transverse to their direction of passage, whereby tension in the filaments at the point of winding on the bobbin is reduced.

2. In a process in which relatively plastic rayon filaments are passed through a guide reciprocating transversely to the direction of passage of the filaments and wound on a rotating annular surface as a series of overlapping spirals, the improvement which comprises immediately before the winding passing the filaments between the guide and said surface against a second annular surface rotating in the direction of passage of the filaments with a peripheral speed higher than that of the first annular surface, transmitting power from the moving surface to the filaments and thereby accelerating the filaments while moving the filaments back and forth across the surface transverse to the direction of passage of the filaments, whereby the tension of the filaments being wound is reduced.

3. In a process in which relatively plastic rayon filaments are passed through a guide reciprocating transversely to the direction of passage of the filaments and wound as a series of overlapping spirals on a rotating collector, the improvement which comprises pressing the filaments passing from the guide to the collector against a surface moving in the direction of passage of the filaments at a speed in excess of that attained by the filaments at the point of winding, said pressing being conducted with a force sufficient to bring about the transmission of power from the moving surface to the filaments and thereby impart acceleration to the filaments, and simultaneously moving the filaments back and forth across said surface transverse to the direction of filament passage, whereby tension in the filaments being wound is reduced.

4. In a process in which plastic rayon filaments are passed through a guide reciprocated transversely to the direction of passage of the filaments and wound as a cake on a collector, the improvement which comprises bending the filaments passing from the guide to the collector over a cylindrical surface rotating in the direction of passage of the filaments at a speed in excess of that attained by the filaments at the point where they are incorporated in the cake, the frictional coefficient of the moving surface and the force with which the filaments are bent over the moving cylindrical surface being such that power

is transmitted from the surface to the filaments and the latter are accelerated and become relatively untensed as they pass to the collector while moving the filaments back and forth across the surface in a direction transverse to that of the moving filaments.

5. In a process in which relatively plastic rayon filaments are passed through a guide reciprocated transversely to the direction of passage of the filaments and wound around a rotating collector, the improvement which comprises passing the filaments between the guide and the collector at least partially around a cylinder disposed with its axis transverse to the direction of passage and rotated in the direction of passage of the filaments at a higher peripheral speed than that of the collector while moving the filaments back and forth across the cylinder in the direction of its axis of rotation, transmitting power from the cylinder to the filaments so that the filaments are accelerated during their contact with the cylinder and are in substantially slack condition when wound on the collector as a series of overlapping spirals.

25 6. In apparatus for winding plastic rayon filaments, the combination which comprises a rotatable bobbin upon which the filaments are wound, means for rotating the bobbin, a guide through which the filaments pass on their way to the bobbin, said guide being reciprocable through a stroke in a direction transverse to that of filament passage and substantially parallel to the axis of rotation of the bobbin, a godet disposed in the path of the filaments from the guide to the bobbin, said godet having a cylindrical surface at least as long as the stroke of the guide and being rotatable around an axis substantially parallel to that of the bobbin, and means for rotating the godet at a peripheral speed in excess of that of the bobbin, the coefficient of friction between the filaments and the cylindrical surface being such that the higher peripheral speed of the cylindrical surface is transmitted at least in part to the filaments.

45 7. In a process in which plastic filaments are passed through a reciprocating guide and wound as a cake on a rotating bobbin, the improvement which comprises passing the filaments back and forth over a roller that is disposed between the guide and the bobbin with its axis of rotation substantially parallel to the bobbin and positively driven at a faster peripheral speed than that of the cake and thus relieving winding tension on the bobbin, whereby variations in tension in successive portions of the filaments being wound tend to be equalized and variations in denier due to stretching of the filaments minimized.

8. In apparatus for winding plastic filaments, the combination which comprises a rotatable bobbin upon which the filaments are wound, means for rotating the bobbin, a guide through which the filaments pass on their way to the bobbin, said guide being reciprocable through a stroke transverse to the direction of passage of the filaments, a godet so disposed in the path of the filaments from the guide to the bobbin that the filaments bear against the godet, and means for rotating the godet in the direction of filament passage at a peripheral speed substantially in excess of that of the bobbin, the coefficient of friction of the godet being such that the higher peripheral speed thereof is transmitted at least in part to the filaments.

9. In apparatus for winding plastic filaments, the combination which comprises a rotatable

bobbin upon which the filaments are wound, means for rotating the bobbin, a guide through which the filaments pass on their way to the bobbin, said guide being reciprocable through a stroke transverse to the direction of passage of the filaments, a godet disposed with its axis of rotation substantially parallel to that of the bobbin and having a rotating surface (against which the filaments bear) at least as long as the stroke

of the reciprocable guide, and means for rotating the godet in the direction of filament passage at a peripheral speed substantially in excess of that of the bobbin, the coefficient of friction of the godet being such that the higher peripheral speed thereof is transmitted at least in part to the filaments.
